UNITED STATES PATENT OFFICE.

HYACINTHE ALPHONSE POVEL, OF PARIS, FRANCE.

VANITY CASE.

Application filed January 6, 1927, Serial No. 159,254, and in France December 1, 1926.

This invention relates to vanity cases and more specifically to vanity cases for holding a powder box for face or other powder as well as a powder puff. The invention relates particularly to the powder box itself which is so constructed as to permit a small quantity of powder to be ejected or forced therefrom when so desired thereby obviating any possibility of loss or waste of the powder.

The principal object of the invention is the production of a vanity case and powder box of the general type heretofore described which shall be simple in construction and of ease and of low cost to manufacture.

A further object of the invention is the production of a vanity case holding a powder box and powder puff and a cover for the case to which a mirror is so attached that when the cover is in closed position on the case the mirror will engage the powder puff adjacent the box, the powder puff providing a protective seat for the mirror and the powder puff then acting from pressure of the mirror to effectively fill the space provided therefor and to close a discharge opening or openings in the powder box.

Further and other objects of the invention will appear from the following description taken in connection with the accompanying drawing in which:

Fig. 1 is a plan view of the blank from which the body of the powder box is constructed.

Fig. 2 is a plan view of the blank from which the tray of the powder box is constructed.

Fig. 3 is a perspective view of the parts constituting the powder box before assembly thereof.

Fig. 4 is a perspective view of the powder box itself after the parts have been assembled.

Fig. 5 is a horizontal cross-section taken through the powder box showing it filled with powder.

Fig. 6 is a perspective view of the vanity case with its cover in open position and with the powder box and a powder puff in position therein.

Fig. 7 is a perspective view of a modified form of powder box.

Referring in detail to the several figures of the drawing, and more particularly to Fig. 6, 1 indicates a walled base of a vanity case having a cover 2 hinged thereto in any

desirable manner, said base and cover being provided with the usual co-operating elements 3 and 4 forming a clasp whereby the cover may be frictionally held in closed position on the base. If so desired the cover may also contain or hold in any convenient manner the mirror 5. The walled base receives the powder puff 6 as well as a powder box 7 the construction of which will presently be described in detail. The powder puff 6 and the powder box 7 fit snugly within the walled base 1 in juxtaposition to each other as shown in Fig. 6.

The blank from which the body of the powder box 7 is constructed is scored as indicated in Fig. 1, the inner scored portions being then bent up to form walls 8 having flanges 9 thereon. Said body is also provided with an opening 10 therein of a size permitting the end of the user's finger to be inserted therein. One of the walls 8 of said body is also provided with an aperture 11. The blank from which the tray of the powder box is constructed is indicated at 12 (see Fig. 2) and is provided with a large rectangular-shaped opening 13 therein and with scored portions 14 which when bent or turned up, form the walls of the tray as indicated in Fig. 3. All of said walls are provided at their edges with ears 15. An aperture 16 is formed in one of the walls 14 and is adapted to register with the aperture 11 in the body 7.

When the powder box is to be loaded with face or other powder the various parts thereof are in the relative position shown in Fig. 3. A membrane or plate 17 of resilient material such as cellophane is provided and is inserted within the body 7 with which it interfits. The tray 12 is then inserted within the body 7 and seated on the resilient membrane 17 which forms a closure for the opening 13, the tray then being filled or packed with the powder 17' (see Fig. 5). The ears 15 on the tray are then bent inwardly at right angles to the position shown in Fig. 3 after which a closing wall 18 constructed of cardboard or any other suitable material is seated on the bent-over ears 15 and the flanges 9 are then bent over onto the closing wall 18 to lock it in position. When the parts have been assembled as just described their relative positions are shown in the sectional view Fig. 5.

When the powder box 7 has been inserted in the vanity case it is in the position shown

in Fig. 6. When it is desired to use some of the powder, the powder puff is removed from the case and the resilient membrane 17 appearing through the opening 10 is tapped to an extent depending upon the amount of powder required. Some of the powder contained in the powder box is thereupon forced or ejected through the aperture 11 onto the base of the vanity case and may be collected by means of the powder puff 6 or otherwise. When the powder box is full of powder the pressure of the resilient membrane thereagainst will force it out of the aperture 11 when pressure is applied against the membrane 17 but if the powder box is partially empty the air pressure exerted against the powder and caused by the tapping of said resilient member ejects the powder from said aperture. When the powder box and powder puff have been placed within the vanity case the powder puff shuts off or closes the aperture 11 thus preventing the accidental escape or loss of powder from the powder box.

It will be understood that various modifications may be resorted to without departing from the spirit of the invention as set forth in the appended claims. Various details of the construction of the vanity case or of the powder box itself could be resorted to and the powder box may be mounted on the cover 2 of the vanity case instead of being held within the body thereof if so desired. Also as shown in the perspective view of Fig. 7 a series of openings 19 could be provided in one of the walls 8 of the body of the powder box and a similar series of openings in a wall 14 of the tray 12 in which case, the apertures 11 and 16 respectively could be dispensed with.

As will be noted from Fig. 6 the mirror 5 preferably is of such size that it occupies the upper part only of the cover 2 so that when the cover is closed the mirror lies on the powder puff 6 adjacent the powder box, said puff acting as a protective seat for the mirror. The mirror also presses against the powder puff when the cover is closed thereby compressing the same and causing it to expand and fill the space provided therefor whereby it will effectively seal or close the aperture 11 and prevent accidental loss of powder.

What I claim as my invention is:

1. In a vanity case, a walled base, a cover therefor, a powder box having an opening therein and fitting within said walled base, a movable member associated with said powder box for discharging powder through said opening when pressure is applied thereagainst and a powder puff also fitting within said walled opening in juxtaposition to said

powder box and acting as a closure for said opening.

2. In a vanity case, a powder box therein having a discharge opening, a resilient membrane or plate forming a part of a wall of said powder box for discharging powder through said opening by pressure applied against said membrane, a powder puff in said vanity case adjacent said opening and a cover for compressing said puff whereby an edge thereof will close said discharge opening.

3. A powder box having a discharge aperture therein and an opening in a wall thereof, a resilient plate within said box, a powder-holding tray engaging said resilient plate and a closure plate engaging said tray, said tray being provided with an aperture corresponding with said discharge aperture and with an opening in the wall thereof adjacent said plate.

4. A powder box having a discharge aperture therein and an opening in a wall thereof, a flange on said box, a resilient plate within said box closing said opening and adapted to discharge powder through said aperture when pressure is applied against said plate, a powder-holding tray engaging said resilient plate and a closure plate engaging said tray and held in engagement therewith by said flange, said tray being provided with an aperture corresponding with said discharge aperture and with an opening in the wall thereof adjacent said plate.

5. A vanity case comprising a walled base holding a powder box having a discharge aperture therein and a powder puff fitting in said case in juxtaposition to said box and adjacent said aperture and a cover for said base having a mirror fastened to a portion only thereof whereby said mirror will engage said powder puff when the cover is in closed position and will compress said puff to cause it to close said discharge aperture.

6. In a vanity case, a powder box therein and a powder puff in juxtaposition to said box, said box having a lateral discharge opening facing said powder puff, a resilient member associated with said powder box for discharging powder through said opening by pressure applied against said resilient member and a cover for said case for closing the same and for applying pressure against said powder puff to cause it to expand whereby it will close said discharge opening.

Signed at New York in the county of New York and State of New York this 5th day of January, A. D. 1927.

HYACINTHE ALPHONSE POVEL.
